UNITED STATES PATENT OFFICE.

ELEAZER KEMPSHALL, OF NEWTON, MASSACHUSETTS, ASSIGNOR TO
THEOPHILUS KING, TRUSTEE, OF BOSTON, MASSACHUSETTS.

DESIGN FOR A LACING-HOOK.

SPECIFICATION forming part of Design No. 25,939, dated August 18, 1896.

Application filed July 20, 1896. Serial No. 599,979. Term of patent 14 years.

To all whom it may concern:

Be it known that I, ELEAZER KEMPSHALL, of Newton, in the county of Middlesex and State of Massachusetts, have invented and 5 produced a new and original Design for Lacing-Hook Blanks, of which the following is a specification.

This invention relates to a new and original 10 design for lacing-hook blanks; and it consists in the novel features of shape and configuration hereinafter fully described and particularly claimed, and clearly illustrated in the drawing.

Reference is to be had to the accompanying 15 drawing, forming a part of this application, in which like characters indicate like parts wherever they occur.

The drawing represents a vertical sectional 20 view of a lacing-hook blank, showing my design.

The essential feature of my design consists 25 in an attaching member terminating in a ring, a neck extending from said ring and carrying a head overhanging and substantially parallel with said ring, said head being formed with a central elevation surrounded by an an-

nular depression, said head terminating in an annular upwardly-extending outwardly-inclined flange.

a represents the attaching member, which 30 may be of one or more parts, terminating in a ring-shaped member *a'*.

b represents a neck extending from one side of said ring-shaped member *a'* and carrying a head *a²*, arranged over, at a slight distance 35 from and substantially parallel with, said member *a'*. The head *a²* is formed with a central elevation or dome *a³*, surrounded by an annular depression *a⁴*. Said head terminates in an upwardly-extending outwardly-inclined 40 flange *a⁵*.

I claim—

The design for a lacing-hook, substantially 45 as shown and described.

In testimony whereof I have signed my 50 name to this specification, in the presence of two subscribing witnesses, this 15th day of July, A. D. 1896.

ELEAZER KEMPSHALL.
